(57) **CLAIM**

The ornamental design for an automobile tire, as shown and described.

DESCRIPTION

FIG. 1 is a perspective view of an automobile tire showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a partially enlarged view of a portion defined by lines 18-18 shown in FIG. 1;

FIG. 9 is a partially enlarged view of a portion defined by lines 19-19 shown in FIG. 2;

FIG. 10 is a cross sectional view of a portion defined by lines 20-20 shown in FIG. 9;

FIG. 11 is an enlarged cross sectional view of a portion defined by lines 21-21 at an area defined by lines X-X shown in FIG. 9;

FIG. 12 is an enlarged cross sectional view of a portion defined by lines 22-22 at an area defined by lines X-X shown in FIG. 9; and,

FIG. 13 is an enlarged cross sectional view of a portion defined by lines 23-23 at an area defined by lines X-X shown in FIG. 9.

In the drawings, the broken lines depict environmental subject matter only and form no part of the claimed design. The dot and dashed lines represents a boundary between the claimed portion and the non-claimed portion.
